SOUND RECORDING SYSTEM

James R. Balsley, Beverly Hills, Calif., assignor,
by mesne assignments, to Westinghouse X-Ray
Company, Inc., Long Island City, N. Y., a cor-
poration of Delaware

Application March 6, 1931, Serial No. 520,730
In Great Britain September 4, 1930

5 Claims. (Cl. 179—100.3)

This invention relates to the recording of sound and particularly to the recording of sound on a photographic film.

The object of this invention is a method of recording sound on a photographic film from which a positive sound record may be produced such that the volume of noise produced during the reproduction of the sound from the positive sound record is materially less than the volume of noise produced from known sound records.

A feature of this invention is a method of recording sound in which the average light energy incident on the negative film varies directly with the envelope of the volume variations of the sound recorder.

Another feature of this invention is a method of recording sound by photographic means in which the average exposure of the negative sound record varies directly with the envelope of the volume variations of the sound recorder.

A further feature of this invention is a method of recording sound which results in the production of a positive photographic record of the sound in which the average transmission of the positive sound record varies directly with the envelope of the volume variations of the sound recorded.

In any known method of recording sound the range of the volumes of sound which may be satisfactorily recorded will be limited by the properties of the recording medium used and the handling which the completed record receives. The least volume of sound which is of interest in recording is that volume of sound which, in reproduction, may be satisfactorily distinguished above the noise produced by irregularities in the structure of the mediums used in recording and reproducing and the dirt, scratches, etc., which collect on the record during its useful life. Recent experiments have shown that the volume of noise produced during the reproduction of a film sound record is approximately proportional to the average transmission of the positive sound record. The average transmission of the sound record may be considered to be equal to the transmission of the unmodulated portions of the sound record. The transmission of a photographic medium is defined as the ratio of the light transmitted through the medium divided by the light incident on the medium and for convenience is commonly expressed as a percentage of the incident light.

Thus, if the average transmission of the positive sound record is varied with the volume of the sound, when the volume of sound is small,

the transmission of the sound record will also be small and the noise produced during reproduction will be small. A reduction in the volume of noise produced from the record will permit smaller volumes of sound to be satisfactorily distinguished from the noise, thus increasing the range of volumes of sound which may be recorded. Or, if the increased range is not utilized, the invention will provide a larger ratio between the present minimum volume of sound and the volume of noise produced during the reproduction of the sound and will thus produce a more pleasing result than known records.

As a photographic positive is an inverse copy of the photographic negative from which the positive was printed, in order for the positive to have a small transmission, the negative must have a large transmission or, as the opacity is by definition the reciprocal of transmission, a small opacity. It is well known that the opacity of a photographic negative is directly proportional to the exposure when the exposure lies within certain limits, and that the exposure is proportional to the product of the intensity of the light incident on the negative multiplied by the time during which the negative is subjected to the light. Thus, assuming that the photographic processes are controlled so that no distortion is produced, the transmission of the positive sound record will be proportional to the exposure of the negative sound record. Accordingly, to produce a positive sound record having a small average transmission, the exposure of the negative sound record must be correspondingly small. In accordance with the invention the intensity of the recording light is varied in accordance with the envelope of the volume variations of the sound recorded to produce a negative sound record having a large average transmission or a small average opacity for small volumes of sound.

In a preferred embodiment of this invention, a recording lamp of the type disclosed in U. S. Patent 1,624,314, patented April 12, 1927, to T. W. Case, may be employed. In known methods of recording sound with a lamp of this type, a constant current flowing through the lamp is adjusted so that in the absence of modulation the light emitted by the lamp is in the middle of the characteristic of the lamp. The gain of the amplifier supplying sound modulated currents to the lamp is then adjusted so that the largest volume of sound to be recorded will just produce complete modulation of the recording lamp. In accordance with the present invention, the sound waves are detected as by a microphone and the

resulting electric currents amplified in the known way and applied to the lamp through a suitable transformer. A portion of the output of the amplifier is supplied through another transformer 5 to the input of a controlling device, such as a thermionic detector. The output circuit of the detector is connected in series with the recording lamp so that the unidirectional current flowing through the lamp also flows through the output circuit of the detector. The impedance of the output circuit of the detector is adjusted so that in the absence of modulation the constant current flowing through the lamp is just sufficient to keep the lamp alight. The sound modulated currents applied to the input of the detector will cause the impedance of the detector to decrease in accordance with the amplitude of the applied currents. This decrease in the impedance of the detector will permit the unidirectional current flowing through the lamp to increase and will thus cause the light energy emitted by the lamp to increase with the volume of the sound. An electrical network having a time constant larger than the period of the lowest frequency to be recorded is inserted in the input circuit of the detector and causes the variation in the impedance of the output circuit of the detector to follow the envelope of the amplitude variations of the sound modulated currents rather than the instantaneous variations in the amplitude.

The drawing is a diagrammatical representation of a typical embodiment of the invention. The sound waves to be recorded are detected by a microphone 1 and amplified in an amplifier 2 which may consist of several stages of amplification in cascade. The output of the amplifier 2 is supplied through a transformer 3 to the input circuit of a thermionic amplifier 4. The output of the amplifier 4 is supplied to the primary windings of the transformers 5 and 6. The transformers 5 and 6 may be combined into one three-winding transformer if desired. Batteries 7 and 8 supply a constant voltage to the control electrode and anode of the amplifier 4 in the usual manner. Any suitable means may be used to heat the cathode of the amplifier 4.

The output of transformer 5 is supplied to a resistance 9 bridged across the secondary winding of the transformer 5. A movable contact 10 taps off a controllable portion of the voltage developed across the resistance 9 and applies this portion to the control electrode 11 of a thermionic triode 12. An electrical network consisting of a high resistance 13 shunted by a condenser 14 is inserted in the connection between the contact 10 and the electrode 11. A potentiometer 15 shunted across a battery 16 supplies an adjustable negative bias to the control electrode 11. The cathode 17 of the thermionic triode 12 is heated by a battery 18. While a thermionic triode has been illustrated, it will be obvious that many other types of vacuum discharge devices may be used and that the invention is not limited to the particular device described.

The anode 19 of the triode 12 is connected through a resistance 20 to one electrode of a recording lamp 21. The other electrode of the recording lamp 21 is connected through the secondary winding of the transformer 6 to a battery 22 in series with battery 8. A unidirectional current will flow from ground on the negative terminal of battery 8 through battery 22, secondary winding of transformer 6, lamp 21, resistance 20, anode 19 of triode 12, through triode 12, to cathode 17 and thence to ground. The current

flowing in this circuit will depend on the characteristics of the lamp 21, and may be adjusted to any desired value by adjusting the voltage of the battery 22 and the negative bias on the control electrode 11.

The light from the recording lamp 21 is directed by a suitable optical system, diagrammatically represented by the lens 23 and slotted plate 24, on a photographic film 25 moved at constant speed by the sprockets 26, 26 in the manner well known in the art.

In an article entitled "Photo-chemical Investigations and a New Method of Determination of the Sensitiveness of Photographic Plates," published in the Journal of the Society of Chemical Industry on May 31, 1890, by Messrs. F. Hurter and V. C. Driffield, the characteristic of a photographic emulsion is shown to consist of four parts, a region of under-exposure, a region of correct exposure, a region of over-exposure and a region of reversal. This characteristic of a photographic emulsion has been studied by many investigators since the publication of this article and the four parts of the characteristic are now well known in the art. In the present invention, in the absence of sound, the bias on the control electrode 11 of the triode 12, and the voltage of the battery 22 are adjusted so that the light emitted by the lamp 21 is at a minimum which preferably should produce an impression at the lower end of the region of correct exposure. This adjustment represents an ideal setting which can only be approximately attained with many of the recording lamps at present in common use. Recent developments in these lamps, however, have shown that by proper design, the lamp may be made to produce more light than prior types and that this adjustment may easily be attained with the latest types of lamps.

It is well known that when light is produced by a discharge of electricity through a gas at low pressure, the voltage at which light is produced, that is, the striking or ignition voltage, is higher than the voltage at which the light disappears, that is, the extinction voltage. In the present invention, the voltage of batteries 8 and 22 in series is preferably adjusted to make the voltage across the lamp 21 slightly greater than the ignition voltage of the lamp so that if a sudden loud sound be detected and the resulting electric current has sufficient amplitude to put out the lamp, the applied voltage will cause the lamp to again emit light as soon as the applied current has decreased. If the electrodes of the lamp are small and compact, the variation in the light is usually a variation in intensity. However, if the electrodes are fairly large and of relatively great length the variation in the light will be more nearly a variation in quantity. Also by the addition of suitable gases, such as the vapor of mercury, the energy emitted by the lamp extends beyond the frequencies included in visible light. In this case, the variation in the energy emitted may be measured in terms of the actinic power, that is the power which causes an impression in the photographic emulsion.

Owing to the electrical network formed by the condenser 14 and resistance 13 in the input circuit of the triode 12, when sound modulated waves are supplied by the transformer 5 to the triode 12, the output impedance of the triode will tend to vary with the envelope of the volume variations of the sound and not with the instantaneous variations. This action is similar to the

action of the well-known detector used in radio receiving sets. A condenser 27 connected across the output circuit of the triode 12 aids in this action. As the current flowing through the lamp 21 must also flow through the triode 12, the change in the impedance of the triode 12 will cause the energy emitted by the lamp to increase and decrease in accordance with the envelope of the amplitude variations of the waves.

10 The sound modulated currents supplied to the primary winding of the transformer 6 will cause an induced current to be developed in the secondary winding of transformer 6 varying with the instantaneous variations in the sound modulated currents. This induced current is superimposed on the current supplied to the lamp 21 and causes the energy emitted by the lamp 21 to vary in accordance with the instantaneous variations in the sound simultaneously with the variation in accordance with the envelope of the volume variations in the sound.

What is claimed is:

1. In combination, a source of sound modulated waves, a photographic medium moved at constant speed, a source of unidirectional electric current, a lamp, an optical system directing the light from said lamp on said medium, a source of current varied in accordance with the instantaneous variations in said waves, a detector, a series circuit connecting said source of unidirectional current, said lamp, said source of varied current and the output circuit of said detector, and means energized by said waves in the input circuit of said detector varying the impedance of the output circuit of said detector in accordance with the envelope of the amplitude variations in said waves.

2. In combination, a source of sound modulated waves, a photographic medium moved at constant speed, a lamp, an optical system directing the light from said lamp on said medium, a source of unidirectional electric current, a source of current varied in accordance with the instantaneous variations in said waves, a detector, a series circuit connecting said source of unidirectional current, said lamp, said source of varied currents and the output circuit of said detector and an electrical network in the input circuit of said detector energized by said waves and having a time constant greater than the period of the lowest frequency of said waves to be recorded on said medium.

3. In combination, a source of sound modulated

waves, a photographic medium moved at constant speed, a lamp, an optical system directing the light from said lamp on said medium, a source of unidirectional electric current, a source of current varied in accordance with the instantaneous variations in said waves, a detector, a series circuit connecting said source of unidirectional current, said lamp, said source of varied current and the output circuit of said detector, means in the input circuit of said detector for adjusting the impedance of the output circuit of said detector so that in the absence of sound modulated waves the lamp is just alight, and other means in the input circuit of said detector to cause the output impedance of said detector to vary inversely with the envelope of the amplitude variations in said waves.

4. In combination, a photographic medium moved at constant speed, a lamp, an optical system directing the light from said lamp on said medium, a source of unidirectional current, a source of current varied in accordance with the instantaneous variations of modulated waves, a detector, a circuit connecting said source of unidirectional current, said lamp, said source of varied current and the output circuit of said detector in serial relation, a biasing voltage in the input circuit of said detector for regulating the impedance of the output circuit of said detector whereby in the absence of modulated waves said lamp produces a desired minimum actinic effect, a network in the input circuit of said detector, comprising a capacitor in parallel relation with a resistor, and a capacitor in parallel relation to the output circuit of said detector cooperating with said input network whereby the output impedance of said detector is varied inversely with the amplitude variations in said waves.

5. A sound-on-film recording apparatus including in combination a film advancing means, means for directing a light beam to the film, a sound sensitive device, an amplifier, the input of which is connected to the sound sensitive device, a rectifying network connected to the output of said amplifier, a recording lamp, a source of electrical energy connected also to the output of the amplifier and to the output of the network, and supplementing current source means maintained charged by means of the network whereby the output energy of the amplifier is at all times stored with current of unchanging polarity but in varying amounts at varying potentials.
